UNITED STATES PATENT OFFICE

130,282

DESIGN FOR A BASE FOR A CHAIR OR THE LIKE

Reginald C. Huntley, Sturgis, Mich.

Application May 31, 1941, Serial No. 101,235

Term of patent 14 years

To all whom it may concern:

Be it known that I, Reginald C. Huntley, a citizen of the United States, residing at Sturgis, in the county of St. Joseph and State of Michigan, have invented a new, original, and ornamental Design for a Base for a Chair or the Like, of which the following is a specification, reference being had to the accompanying drawing, forming part thereof, in which:

Fig. 1 is a perspective view of a base for a chair or the like, showing my new design, and

Fig. 2 is an enlarged side elevational view of the base viewing one of the legs from its end.

The dominant feature of my design resides in the outward bulging of the outer ends of the legs to form rounded enlargements which extend substantially to the floor as shown.

I claim:

The ornamental design for a base for a chair or the like, substantially as shown and described.

REGINALD C. HUNTLEY.
